UNITED STATES PATENT OFFICE.

HENRY E. HACKMAN, OF FORT WAYNE, INDIANA.

SLIDING DOOR.

Application filed August 21, 1925. Serial No. 51,614.

To all whom it may concern:

Be it known that I, HENRY E. HACKMAN, a citizen of the United States, residing at Fort Wayne, in the county of Allen and 5 State of Indiana, have invented new and useful Improvements in Sliding Doors, of which the following is a specification.

The invention relates to sliding doors and particularly to doors adapted to close a relatively wide opening, such as a garage entrance, wherein the entrance is preferably closed by a plurality of doors.

The object of the invention is to provide a simple mechanism by which a plurality of 15 doors may be supported for movement from an aligned condition in the closed position to a lapped condition, or one behind the other, in the open position.

The invention consists in the novel construction, arrangement and combination of parts hereinafter described and illustrated in the accompanying drawings.

In the illustrative embodiment of the invention, Figure 1 is an elevational view of 20 the doors in closed condition; Fig. 2 a plan view of the same; Fig. 3 a plan view of the lower guide rail and switch tracks; Fig. 4 an end elevational view of the middle door; Fig. 5 a plan view of the upper track and 25 switch tracks with the supporting members of one of the doors entering one of the switches; Fig. 6 a side elevational view of the upper rail at the forward switch tracks; Fig. 7 an end elevational view of the same; Fig. 8 a side elevational view of the upper rail at the rear switch tracks; Fig. 9 an end elevational view of the same; Fig. 10 a plan view of the lower rail and switch 30 tracks; Fig. 11 a side elevational view of the lower rail at the forward switch tracks; Fig. 12 an end elevational view of the same; Fig. 13 a side elevational view of the lower rail at the rear switch tracks; Fig. 14 an end 35 elevational view of the same; Fig. 15 a plan view of two of the doors illustrating the coupling therefor; Fig. 16 a side view of the same; Fig. 17 a plan view of the upper guides for the first door; Fig. 18 a plan view of the upper guides for the second door; Fig. 40 45 50 55

second and third doors; Fig. 25 an end elevational view of the same; Fig. 26 a plan view of the pivot for the shoes and Fig. 27 a side view of the same.

Referring to the illustrative embodiment of the invention, 1 represents the frame of a housing that, in practice, is installed in the building adjacent to one side of the door opening. One end of the rail 2 is supported by this frame or the rail is otherwise supported over and across the door opening, upon which the doors 3, 4 and 5 are supported or hung by the roller hangers 6. Two switch tracks 7 and 8 are secured to the side member 1^a of the frame 1 and are parallel to the rail 2 for a portion of their length, the forward end of each switch track being curved toward the rail and the forward extremity of the switch 8 being closer to the rail than the forward extremity of the switch 7. Two switches 9 and 10 similar to switches 7 and 8 respectively are similarly secured to the member 1^b of the frame and similarly disposed with respect to the rail 2. This rail is undercut at 11 and 12 between the ends of the opposite switches for the purpose hereafter described.

A rail 13 extends across the lower side of the door opening in the building and into the frame or housing 1. Two switches 14 and 15 are secured to the lower member 1^c of the frame 1 similarly to switches 7 and 8, the forward end of each switch 14, 15 being adjacent or engaged to the side of the rail 13, and two switches 16 and 17 are similarly secured to the member 1^d of the frame 1 and their forward ends adjacent or engaged to the rail 13. At the junction point of the switches 14 and 16 with the rail, the rail and switches are cut out to form a passage way 18, and a similar passageway 19 is formed at the junction point of the switches 15 and 17 and the rail 13.

At the rear end of the top of the door 3 there is mounted a latch 20 adapted to engage a similar latch 21 mounted at the forward end of the top of the door 4 and similar latches 22 and 23 are mounted on the rear end of the top of the door 4 and the forward end of the door 5 respectively, the latches being adapted to couple the doors together. Each of the latches (Figs. 15, 16) comprises a notched bar 24 pivoted within a housing 25, a spring 26 disposed in a socket 27 formed in the bottom member of the housing 25 tending to hold the bar away

from the side 25^a of that housing, or in contact with the opposite side of the housing as shown in outline in Fig. 15, so that, upon sliding the doors, when two adjacent 5 latches 20 and 21, engage, the springs will cause the latches to firmly grip each other and couple the doors together.

The hangers for the doors are alike in their general features. Each hanger comprises a frame 28^a (Fig. 7) having the wheels 29 journaled at its upper end and adapted to roll on the rail 2. The lower end of each hanger is bent laterally and then upwardly, the lateral portion having an extension 28^b that is pivoted at 31^a (Fig. 1) to a bracket secured to the top of the door, and the said upward extension being disposed upon the opposite side of the rail to form a guard 30. Wings project from the opposite edges of the frame at a selected point to form a guide 31. These wings are either in the vertical plane of the frame or they are curved outwardly. In the hangers 33 for the first door 3 the guides 34 are in the vertical plane of the frame (Fig. 17) and the guards 30^a are also straight or parallel to the rail 2. The hanger 28 for the middle door is above described and in the other hanger 34^a for said door the curvature of the upper guide 35 is not as great as that of the guide 31 so that it will pass between the ends of the switch tracks 7 and 9 and will not pass between the ends of the switch tracks 8 and 10, but its ends will project laterally beyond or forwardly of the end of the switch track 10 and abut the outer face thereof as the door is moved to open position and thereby divert the rollers to said switch track. The guide 31 of the forward hanger of the middle door will abut the outer face of the switch track 9 and divert the rollers of that hanger onto the latter track. In this diverting movement of the hangers 28 and 34^a the guards 30 and 36 pass through the cut-out portions 11 and 12 respectively. The cut-out portion 12 is higher than the portion 11 and the guard 36 is higher than the guard 30. This difference in height of the cut-out portions and 50 of the guards 30, 36 is provided so that the guard 36 will not pass into the cut-out portion 11 and derail the hanger 28. The hangers 37 and 38 for the third door 5 are similar to the hangers 28 and 34^a respectively, the only difference being that they are reverse on their pivots so that the guides 39 and 40 thereon will abut the outer faces of the switch tracks 7 and 8 and divert the hangers to those tracks, the guards 41 and 42 passing through the cut-out portions 11 and 12.

Shoes 41, (Figs. 20 and 21) are pivoted by the member 42, Figs. 26, 27 to the bottom of the first door 3. Shoes 43, 44 are 65 similarly pivoted to the bottom of the mid-

dle door 4 and the shoes 45, 46 are similarly pivoted to the third door 5 and all said shoes slide in the rail 13. Each of the shoes is U-shaped in cross section, the depending legs 41^a of the shoes 41 being of uniform thickness from end to end, and the depending legs of the other shoes being longitudinally rounded off on their inner surfaces. The front shoes 43 and 45 of the doors 4 and 5 are alike and the rear shoes 44 and 46 are also alike, the shoes on the door 5 being reversed on the track so that the vertically longer legs 45^a and 46^a of those shoes will be disposed on the rear side of the rail 13, whereas the corresponding legs of the shoes 43, 44 are disposed on the front side of that rail as shown in Fig. 1. The cut-out portion 19 in the rail 13 is deeper than the cut-out portion 18 therein, and the inside legs of the rear shoes 44 and 46 pass through the cut-out portion 19 but will not pass through the cut-out portion 18, and the inside legs on the forward shoes 43 and 45 will pass through the cut-out portion 18.

When the doors are enclosed in the housing the first door 3 is intermediate the doors 4 and 5, the door 5 being the outermost since it is now supported on the switch rails 7 and 8 and the door 4 is supported on the switch rails 9 and 10. To close the doors 40 the door 3 is drawn on the rail 2 out of the housing, the latch 20 eventually engages the latch 21 on the door 4 and said door is pulled along with the first door. The curved ends of the switch tracks 9, 10, 16 and 17 direct the hangers and the shoes on said door 4 toward the rails 2 and 13, the forward ends of the upper guides on the hangers abutting the side of the rail and the forward curved ends of the inner legs of the shoes abutting the forward edges of the cut-out portions 18 and 19 in the rail 13, and thereby causing the hanger rollers to ride onto the rail 2 and the shoes to ride onto the rail 13. The continued movement of the doors 3 and 4 causes the latch 22 on the door 4 to engage the latch 23 on the door 5 and causing the latter door to move from the switch tracks 7 and 8 onto the rail 2, similarly to door 4.

In opening the doors the movement and action of the parts are the reverse of that of the closing movements and actions.

The operation of the doors is smooth and easy and their coupling is positively accomplished to close the doorway. When the doors are opened they are fully housed in a minimum of space.

What I claim is:

1. The combination with a plurality of doors, of a main rail fixed above the doors, hangers for and pivoted to each door and adapted to be moved on the rail, switch rails fixed adjacent to the main rail and adapted to support a portion of the doors in open

position and in parallel relation, and means on the hangers of the said portion of the doors adapted to engage the switch rails selectively for diverting the hangers onto said 5 switch rails in the opening movement of the doors.

2. The combination with a plurality of doors, of an upper main rail, switch rails fixed adjacent to opposite sides of one end 10 of the main rail and parallel thereto, said switch rails having one end extending toward the said main rail, hangers for and pivotally connected to the doors and adapted to ride on the main rail, means on the 15 hangers of a portion of the doors to cooperate with selected switch rails to divert said hangers onto said switch rails in the opening movement of the doors for causing said portion of doors to move into parallel 20 relation, means to guide the bottoms of the doors and means to automatically and releasably couple the doors together in their closing movement.

3. The combination with a plurality of 25 doors, an upper main rail, a lower main rail, switch rails upon opposite sides of one end of each main rail, hangers movable on the upper rail and pivotally connected to the doors, shoes pivoted to the doors and 30 slideable on the lower rail, the hangers and shoes on a portion of the doors being adapted to engage selected switch rails, in the opening movement of the doors, for diverting the said doors onto said switch rails and causing 35 the said doors to move into parallel relation, said hangers and shoes also causing the said doors to move onto the main rails in the closing movement thereof, and means carried by the doors for automatically coupling 40 them together in the opening movement thereof.

4. The combination with a plurality of doors, of an upper main rail, a lower main rail, switch rails upon opposite sides of the 45 main rails at one end thereof and spaced

therefrom, hangers pivoted to the doors and adapted to ride on the main rail, shoes pivoted to the doors and adapted to ride on the lower rail, one of the doors being adapted to be continuously supported on the main 50 rails, guides on the hangers and shoes of the remaining doors adapted to engage selected switch rails for diverting said remaining doors onto said switch rails in the opening movement of the doors to cause all the doors 55 to move into parallel arrangement at said ends of the main rails and means to automatically couple the doors together when the door on the main rails is moved thereon to closed position for drawing the remaining doors successively from the switch rails into alignment on the main rails.

5. The combination with a plurality of doors, of an upper main rail, a lower main rail, switch rails upon opposite sides of the 65 said main rails at one end thereof, each switch rail having one end thereof extending toward the main rail, each rail having cut out portions adjacent the latter ends of the switch rails, hangers pivoted to the 70 doors and adapted to ride on the upper main rail, shoes pivoted to the doors and adapted to ride on the lower rail, the hangers and shoes having guides thereon some of which are adapted to engage selected switch rails 75 for diverting the doors that are pivoted to the selected hangers and shoes onto the said switch rails in the opening movement of the doors, guards on the hangers and shoes adapted to pass through certain of said cut 80 out portions, means to automatically couple the doors together in the closing movement thereof, whereby the closing movement of one of the doors on said main rails causes the remaining doors to move onto the main 85 rails successively in alignment.

In witness whereof I hereunto subscribe my name this 18th day of August, 1925.

HENRY E. HACKMAN.
